UNITED STATES PATENT OFFICE.

GEORGE W. PIGGOTT, OF NEW YORK, N. Y., ASSIGNOR TO HARTFORD CARPET COMPANY, OF HARTFORD, CONNECTICUT.

DESIGN FOR CARPET.

SPECIFICATION forming part of Design No. 11,852, dated July 6, 1880.

Application filed February 12, 1880. Term of patent 3½ years.

To all whom it may concern:

Be it known that I, GEORGE W. PIGGOTT, of the city, county, and State of New York, have invented a new and original Design for 5 a Carpet, of which the following is a specification.

This invention relates to a new and original design for carpets, oil-cloths, and similar fabrics.

10 It consists in the novel grouping and configuration of figures, hereinafter more fully described and claimed.

The accompanying photograph illustrates a face view of a carpet having my new design.

15 On the background of the carpet is an L-shaped figure, A, with flowers and leaves interspersed upon its ground. B is an irregularly-shaped figure with flowers and leaves on its ground, a border, d, on its upper side, and 20 a triangular ornament, e, at the upper corner. C is a rectangular figure with flowers interspersed over its surface. D is an L-shaped flowered figure with a border, g. E is also a zigzag-shaped flowered figure with a border, 25 h. F is an L-shaped figure with leaves imposed on its surface. G is a rectangular figure with borders i j, and with flowers and leaves interspersed over its surface. H is a square figure. I is a group of flowers imposed 30 on the surfaces or grounds of figure H and the irregular figure k, which has a border, l. m is a border placed between figure F and figures C D. Vines and flowers are profusely represented on the several figures, and overlap and 35 connect the same, as shown.

I claim—

1. The design for a carpet, consisting of the figure A, substantially as shown.
2. The design for a carpet, consisting of the figure C and the border g, substantially as 40 shown.
3. The design for a carpet, consisting of the L-shaped figure D and border h, substantially as shown.
4. The design for a carpet, consisting of the 45 figure E and border h, substantially as shown.
5. The design for a carpet, consisting of the figure F, substantially as shown.
6. The design for a carpet, consisting of the figures A B C D E F, and borders d, g, h, and 50 m, and connecting vines and flowers, substantially as shown.
7. The design for a carpet, consisting of the figures G H and borders i j, substantially as shown.
8. The design for a carpet, consisting of the group I and figures H k and borders j l, substantially as shown.
- 55 9. The design for a carpet, consisting of the figures C D E F and border m, substantially 60 as shown.
10. The design for a carpet, consisting of the figures A B C D E F G H k, floral group I, and borders d g h i j l m, corner ornament, e, and intervening and connecting flowers, vines, 65 and leaves, substantially as shown.
